UNITED STATES PATENT OFFICE.

WILLIAM J. BODA, OF DAYTON, OHIO, ASSIGNOR OF ONE-HALF TO LEE M. BODA, OF COLUMBUS, OHIO.

WINDOW STRUCTURE.

Application filed April 20, 1921. Serial No. 462,812.

To all whom it may concern:

Be it known that I, WILLIAM J. BODA, a citizen of the United States, residing at Dayton, in the county of Montgomery and State of Ohio, have invented certain new and useful Improvements in Window Structures, of which the following is a specification, reference being had therein to the accompanying drawing.

10 This invention relates to window structures and one object of the invention is to provide such a structure which will be dust and wind proof.

15 A further object of the invention is to provide such a structure which will be simple in its construction and inexpensive to build and which will be of such a character that the sash can be readily removed.

20 A further object of the invention is to provide a sash tightening device of a simple effective character.

A further object of the invention is to provide such a window structure with movably mounted pulleys for the sash.

25 Other objects of the invention will appear as the device is described in detail.

In the accompanying drawings Fig. 1 is a front elevation of a window embodying my invention; Fig. 2 is a perspective detail view of the intermediate frame; Fig. 3 is a horizontal section taken on lines 3'-3' of Figs. 1 and 4; Fig. 4 is a vertical sectional view, partly broken away, taken on the line 4'-4' of Fig. 1; Fig. 5 is a

30 plan view of the locking device; Fig. 6 is a detail view of the angular plate forming part of the sash tightening device; Fig. 7 is a side elevation, partly broken away, of the inner face of the upper sash; Fig. 8 is an

35 elevation of the outer side of the lower sash, partly broken away; Fig. 9 is a sectional view of a portion of the structure showing the movable sash pulley in side elevation; Fig. 10 is a sectional view of the structure

40 showing an edge view of the movable sash pulley; Fig. 11 is a perspective detail view of the supporting block for the sash pulley; and Fig. 12 is a sectional detail view of one of the sashes showing a modified form of packing.

In these drawings I have illustrated one embodiment of my invention and have shown the same as comprising side and top frame members 1 and 2, respectively, which here

50 comprise merely strips of wood of the proper

width and thickness. Inasmuch as these strips, or frame members, are entirely enclosed they may be of inexpensive material of any suitable kind. Secured to the outer edge of the frame member are finishing strips, or guide strips, 3 which project beyond the face of the frame member and overlap the adjacent edges of the sash. Other finishing strips, or guide strips, 4 are secured to the frame member at the inner edge thereof and likewise overlap the adjacent edges of the sash. The space between the two guide strips is divided by an intermediate frame member into two pockets, or guideways, in each of which is mounted a sash, the upper sash, 5, being mounted in that pocket adjacent to the guide strip 3 and the lower sash, 6, being mounted in the pocket, or guideway, adjacent to the guide strip 4. The intermediate frame may be of any suitable character but it preferably consists of vertical side members 7 and upper and lower transverse members 8 and 9, respectively, and an intermediate or central transverse member 10. The intermediate transverse member, or permanent locking rail, 10 is so arranged that when both sashes are in their closed position it will lie between the top and bottom rails, respectively, of the lower and upper sashes. This frame may be mounted in the main frame in any suitable manner but, as here shown, I have secured to each frame member, 1 and 2, adjacent to the guide strip 3, a spacing strip 11 which is of a width slightly greater than the thickness of the sash rail and of a thickness less than the width of that portion of the guide strip which projects beyond the inner face of the frame member. In assembling the window structure the guide strips 3 are first secured to the frame and the spacing strips 11 then placed in position and the upper sash inserted. After this the intermediate frame is placed in position against the edges of the strips 11 and spacing strips 12, similar to the strips 11, are secured to the frame members between the intermediate frame member and the inner guide strips 4, the latter being applied after the lower sash has been inserted. The spacing strips 12 are preferably attached to the frame members by screws, as shown at 13, so that they can be readily removed, after the guide strips 4 have been removed, to permit of the removal of the intermediate frame and the sashes. The

105
110

spacing strips 11 and 12 serve not only to properly locate the intermediate frame with relation to the guide strips but they also serve to prevent the warping or distortion 5 of the intermediate frame. Further, these spacing strips being of a width greater than the thickness of the sashes provide guideways of ample width to receive the sashes, thus avoiding any difficulty, or dressing 10 down of the sashes, in assembling the window structure. It will be noted that all the sash rails are of uniform thickness, thus enabling the finished sash to be passed through a sander, or other suitable device, and 15 dressed to an exact standard thickness which is preferably one-sixteenth of an inch less than the width of the spacing strips.

The inner face of each rail of the upper sash, and the outer faces of the top and 20 side rails of the lower sash, that is, the faces adjacent to the intermediate frame, are recessed to form longitudinal extending 25 channels 14. In each channel is mounted a packing adapted to bear against the adjacent surface of the intermediate frame and form dust and wind proof joints. Preferably this packing is in the form of a strip of metal 15 secured at one edge to the bottom of the channel and curved so that the 30 resilient body portion thereof will bear against the intermediate frame, thus maintaining a tight joint even though there should be some movement of the sash away from the intermediate frame members. In 35 the case of the bottom rail of the lower sash the channel is formed in the edge of the window stool 16, as shown at 17, and a packing strip 18, similar to the strips 15 is mounted therein, thus placing the packing between 40 the window stool and the sash rail, instead of between the sash rail and the intermediate frame.

In order that the sash may be retained 45 in position to hold the packing firmly against the intermediate frame without the necessity of fitting each sash too tightly in its guideways, or pockets, I have provided a sash tightening device which I have applied to the upper portion of the upper sash. 50 and to the lower portion of the lower sash. This sash tightening device may take various forms, but in the present instance, I have shown it as comprising a bracket, or angular bar, 19 rigidly secured to a fixed 55 part of the window structure adjacent to the upper or lower sash rail, as the case may be, and in the present instance I have secured these brackets to the guide strips 3 and 4, respectively. Each bracket has an 60 inclined surface 20 arranged to be engaged by an adjustable stop carried by the sash and this stop may, if desired, be in the form of a screw 21 inserted in the sash. By properly adjusting the screw head with 65 relation to the inclined surface of the bracket

the tightening device will force the sash into engagement with the intermediate frame when it is moved to its closed position. This sash tightening device, while of particular advantage in the present construction may be used as a sash tightening device independently of the other features of the present invention. The lower rail of the upper sash and the upper rail of the lower sash are held in engagement with the 70 central bar of the intermediate frame by means of a suitable fastening device, which is here shown as comprising a locking bar, or latch, 22 pivotally mounted on one of the sash rails and adapted to extend across the 75 intermediate frame member, or locking rail, and having at its other end a recessed portion 23 to receive a locking stud 24 secured to the other sash rail, thus locking the two 80 sash rails one to the other and at the same time drawing them snugly into engagement with the permanent locking rail. In order that the sash may be locked to the permanent locking rail of the intermediate frame as well as to one another, I have provided that rail with a locking member 25 having an overhanging portion beneath 85 which the locking bar 22 is moved, as shown in Fig. 5.

In order that the intermediate frame may 90 be removed from a window structure the sash pulleys, one of which is shown at 26, are mounted in slots 27 in the frame member and are movably supported therein by means of arms 28 which are pivotally mounted 95 at their upper ends on the frame member above the slot 27. In the present construction I have provided a supporting member, or block, 29 to which the arms 28 are pivotally attached, and as here shown, 100 this member comprises a cylindrical block adapted to be inserted in an auger hole in the frame member and having in its lower side a recess 30 into which the arms 28 extend and in which they are pivotally mounted by means of a pivot pin 31 extending through the side walls of the recess. It will be apparent, therefore, that when it is desired to remove the intermediate frame the inner guide strip and the inner spacing strip 115 are removed, and the sash pulleys 26 swung outwardly out of the path of the intermediate frame, thus leaving a clear path for the removal of that frame.

In order to prevent the accumulation of 120 water between the lower sash and the transverse member 9 of the intermediate frame I have provided the member 9 of the intermediate frame with a plurality of transverse slots, or grooves, 34 in that edge thereof 125 of which rests upon the window sill and, if desired, that surface of the member 9 adjacent to the lower sash may be provided with vertical grooves 35 which will further facilitate the escape of any water which would 130

otherwise accumulate in the space between the sash and the frame member.

It will be apparent from the foregoing description that I have provided a window structure which is simple in its construction and can be easily constructed at a low cost, and which will be dust and wind proof. It will further be noted that by means of this construction I am enabled to form the inner surfaces of the locking rails of the two sashes flush with the inner surfaces of the side rails thereof, thereby avoiding the use of the projecting lock rail which is commonly employed with a sash of this character. The resilient packing strips, or springs provide a very permanent packing, but it is not necessary that the metal packing should be employed as an ordinary felt strip may be inserted in the recesses, as shown at 32 in Fig. 12.

While I have shown and described one embodiment of my invention I wish it to be understood that I do not desire to be limited to the details thereof as various modifications may occur to a person skilled in the art.

Having now fully described my invention what I claim as new and desire to secure by Letters Patent, is:

1. In a window structure, a main frame, guide strips secured to the inner and outer portions of said main frame, an intermediate frame removably mounted in the main frame and comprising side members and transverse members connecting said side members one to the other, spacing strips interposed between said side members and the respective guide strips to maintain said side members within said frame and in proper spaced relation to said guide strips, and sashes mounted between said intermediate frame and said guide strips.

2. In a window structure, a main frame, guide strips secured to the inner and outer portions of said main frame, an intermediate frame removably mounted in the main frame and comprising side members and transverse members connecting said side members one to the other, spacing strips interposed between said side members and the respective guide strips to maintain said side members within said frame and in proper spaced relation to said guide strips, and sashes mounted between said intermediate frame and said guide strips, said sashes being of a thickness less than the width of said spacing strips.

3. In a window structure, a main frame, guide strips secured to the inner and outer portions of said main frame, an intermediate frame removably mounted in the main frame and comprising side members and transverse members connecting said side members one to the other, spacing strips interposed between said side members and the respective guide strips to maintain said side

members within said frame and in proper spaced relation to said guide strips, and sashes mounted between said intermediate frame and said guide strips, packing strips carried by said sashes and arranged to engage the intermediate frame to form tight joints between said frame and the respective sashes, and means to press said sashes toward said intermediate frame when said sashes are in their closed positions.

4. In a window structure, a main frame, guide strips secured to the inner and outer portions of said main frame, an intermediate frame removably mounted in the main frame and comprising side members and transverse members connecting said side members one to the other, spacing strips interposed between said side members and the respective guide strips to maintain said side members within said frame and in proper spaced relation to said guide strips, and sashes mounted between said intermediate frame and said guide strips, packing strips carried by said sashes and arranged to engage the intermediate frame to form tight joints between said frame and the respective sashes, and sash tightening devices each comprising a member secured to one of said guide strips and having an inclined surface, and a stop carried by the adjacent portion of the sash and arranged to engage said inclined surface when the sash is moved to its closed position.

5. In a window structure, a main frame, guide strips secured to the inner and outer portions of said main frame, an intermediate frame removably mounted within said main frame and comprising vertical side members, top and bottom transverse members and an intermediate transverse member, sashes mounted between said intermediate frame and the respective guide strips, and means to hold the lower rail of one of said sashes in engagement with said bottom transverse member.

6. In a window structure, a main frame, guide strips secured to the inner and outer portions of said main frame, an intermediate frame removably mounted in said main frame and comprising vertical side members, top and bottom transverse members and an intermediate transverse member, spacing strips interposed between the side members of said intermediate frame and the respective guide strips to retain said intermediate frame in position within said frame, and sashes mounted between said intermediate frame and the respective guide strips.

7. In a window structure, a main frame, guide strips secured to the inner and outer portions of said main frame, an intermediate frame mounted within said main frame and comprising vertical side members, top and bottom transverse members and an intermediate transverse member, sashes mounted between said intermediate frame and the

- respective guide strips, packing strips carried by certain of the rails of said sashes and arranged to engage the corresponding portions of said intermediate frame, a locking device connected to the lower rail of one of said sashes and adapted to extend across the intermediate member of said intermediate frame and to engage a part on the upper rail of the other of said sashes and move said rails of said sashes one toward the other, and a device carried by the intermediate member of said intermediate frame and having a part to extend above said locking device.
8. In a window structure, a frame, guide strips secured to the inner and outer portions thereof, an intermediate frame mounted within the first mentioned frame and spaced from both the inner and outer guide strips, said intermediate frame comprising side members, top and bottom transverse members, and an intermediate locking rail, sashes mounted in the spaces between said intermediate frame and the respective guide strips, packing strips carried by said sashes and arranged to bear against said intermediate frame, a locking device connected to the lower rail of one of said sashes and adapted to extend across the locking rail of said intermediate frame and to engage a member on the upper rail of the other of said sashes, a locking member carried by the locking rail of said intermediate frame to engage said device, brackets secured to said first mentioned frame near the upper and lower portions thereof and having inclined surfaces, and adjustable stops carried by said sashes and arranged to engage the inclined surfaces of said brackets.
9. In a window structure, a frame, guide strips secured to the inner and outer portions of said frame, an intermediate frame comprising side members and upper and lower transverse members arranged within the first mentioned frame and spaced from said guide strips to form guideways therewith, sashes mounted in said guideways, the lower transverse member of said intermediate frame having openings to permit the escape of water from between the same and the adjacent sash, and means for moving the lower rail of the inner sash into contact with said lower transverse member.
10. In a window structure, a frame, guide strips secured to the inner and outer portions of said frame, an intermediate frame comprising side members and upper and lower transverse members arranged within the first mentioned frame and spaced from

said guide strips to form guideways therewith, and sashes mounted in said guideways, means for forming tight joints between the sashes and the intermediate frame, the lower transverse member of said intermediate frame having openings to permit the escape of water from between the same and the adjacent sash, and means for pressing the lower rail of the inner sash into contact with said lower transverse member.

11. In a window structure, a main frame, guide strips secured to the inner and outer portions of said frame, an intermediate frame removably mounted within said main frame and spaced from the respective guide strips to form guideways therewith, sashes mounted in said guideways, said main frame having slots in the upper portions thereof opening into the respective guideways on one side of said intermediate frame, sash pulleys arranged in said slots, and means for movably supporting said pulleys on said main frame to permit them to move into and out of the respective guideways.

12. In a window structure, a frame, guide strips secured to inner and outer portions of said frame, an intermediate frame mounted within the first mentioned frame and spaced from the respective guide strips to form guideways therewith, sashes mounted in said guideways, said main frame member having slots opening into the guideways on one side of said intermediate frame, sash pulleys mounted in said slots, supporting arms connected with said pulleys, and means for pivotally connecting the upper ends of said arms with said main frame whereby said pulleys may be moved bodily out of the respective guideways.

13. In a window structure, a frame, guide strips secured to the inner and outer portions of said frame, an intermediate frame mounted within the first mentioned frame and spaced from the respective guide strips to form guideways therewith, sashes mounted in said guideways, said main frame having slots opening into the guideways on one side of said intermediate frame, sash pulleys mounted in said slots, supporting arms connected with said pulleys, supporting blocks mounted in said main frame above the respective slots and having recesses in the lower portions thereof to receive the upper ends of said arms, and means for pivotally connecting said arms to said blocks.

In testimony whereof, I affix my signature hereto.

WILLIAM J. BODA.
